UNITED STATES PATENT OFFICE

DONALD L. SANZENBACHER, OF BRONSON, MICHIGAN, ASSIGNOR TO L. A. DARLING COMPANY, OF BRONSON, MICHIGAN, A CORPORATION OF MICHIGAN

DESIGN FOR AN ARTICLE DISPLAY PEDESTAL

Application filed April 17, 1933. Serial No. 47,817. Term of patent 7 years.

To all whom it may concern:

Be it known that I, DONALD L. SANZENBACHER, a citizen of the United States, and resident of Bronson, county of Branch, State of Michigan, have invented a new, original, and ornamental Design for an Article Display Pedestal, of which the following is a specification, reference being had to the accompanying drawing forming a part thereof.

The drawing is a perspective elevation of an article display pedestal showing my new

design with the top and base thereof in dotted lines.

The dominant feature of the design resides in the upright legs.

I claim:

The ornamental design for an article display pedestal, substantially as shown and described.

In testimony whereof I have hereunto signed my name to this specification.

DONALD L. SANZENBACHER.
